[57] CLAIM

The ornamental design for a vapor hood for hair care, as shown.

DESCRIPTION

FIG. 1 is a perspective view taken from the top, front and left side of a vapor hood for hair care embodying my new design;

FIG. 2 is a front elevational view thereof;

FIG. 3 is a right side elevational view thereof;

FIG. 4 is a top plan view thereof; and

FIG. 5 is a rear elevational view thereof.
